UNITED STATES PATENT OFFICE

118,522

DESIGN FOR A NURSERY LAMP

Lewis P. Weil, Germantown, Pa.

Application November 4, 1939, Serial No. 88,034

Term of patent 7 years

To all whom it may concern:

Be it known that I, Lewis P. Weil, a citizen of the United States, residing in Germantown, in the county of Philadelphia, State of Pennsylvania, have invented a new, original, and ornamental Design for a Nursery Lamp, of which the following is a specification, reference being had to the accompanying drawing, forming part thereof.

Fig. 1 is an elevational view of the nursery lamp showing my new design.

Fig. 2 is a similar view showing the head turned on its base, the hand being fixed on the base.

Fig. 3 is a side elevation.

I claim:

The ornamental design for a nursery lamp, as shown.

LEWIS P. WEIL.
